UNITED STATES PATENT OFFICE.

HARRY M. SMITH, OF NEAR KNOXVILLE, TENNESSEE, ASSIGNOR TO FRANK J. JONES, OF KNOXVILLE, TENNESSEE.

COOKING-RANGE.

No. 927,437.

Specification of Letters Patent.

Patented July 6, 1909.

Application filed April 20, 1908. Serial No. 428,203.

To all whom it may concern:

Be it known that I, HARRY M. SMITH, a citizen of the United States, residing near Knoxville, in the county of Knox and State 5 of Tennessee, have invented a new and useful Improvement in Cooking-Ranges, of which the following is a specification, reference being had to the accompanying drawing.

My invention relates to cooking ranges 10 comprising oven chambers.

The object of the invention is to provide for the economical utilization of heat for the heating of the oven chambers.

In the accompanying drawings, Figure 1 15 is an upright section on the line 1—1 of Fig. 2; Fig. 2 is an upright section on the line 2—2 of Fig. 3; Fig. 3 is an elevation of one of the upright walls of the range; Fig. 4 is a plan of a portion of the top of the range; 20 Fig. 5 is a perspective of the grate.

By way of general description, it may be stated that, in the form shown in the drawings, the range comprises four oven chambers in the body of the range and a fifth oven 25 chamber extending partially above the body of the range. The said four oven chambers are separated far enough from each other to permit the placing of the fire grate intermediate said chambers so that fire upon said 30 grate will transmit heat to all of said chambers. And all of said chambers are so separated from each other as to increase the number of walls which can receive heat from said fire. Two of said oven chambers have open- 35

ings or doors through one of the upright walls of the range and the other two of said chambers have openings or doors through the opposite upright wall of the range. For convenience in description, said walls will be 40 herein termed the side walls of the range, while the other two upright walls of the range are termed the end walls. Said end walls cover the ends of said oven chambers as well as the fire box and flues.

45 A, A designate said side walls; B, B designate said end walls; and C designates the bottom wall. Said side and end walls are preferably extended below said bottom wall to hold the latter above the floor, as shown in 50 the drawings.

D, D are horizontal top plates, between which rises a half-cylindrical tubular top plate, E.

F, F are two lower oven chambers each

formed by the bottom wall, C, side walls, A, 55 end walls, B, an upright wall, 1, and a sloping top wall, 2. The walls, 1, 1, are separated sufficiently to make a space for an ash pan, 3. Said oven chambers have doors, 4, 4. Above each chamber, F, is an oven chamber, G, each formed by the side walls, A, end walls, B, a bottom wall, 5, a low upright wall, 6, and a sloping upper wall, 7. Said walls, 6, 6, are separated from each other sufficiently to make room for a fire box; and the bottom walls, 5, 5, are high enough above the top walls, 2, of the chambers, F, to form a space, I, at each side of the grate, 8. At the level of the lower edges of said side walls is located a trough-form grate, 8, having at 60 its ends journals, 9, extending through bearings, 10, in the end walls, B, of the range. The projecting ends of said journals may be engaged for turning said journals and the 65 grate for dumping ashes or cinders from the grate into said ash pan. Within the half-cylindrical top plate, E, and extending a little below the level of the top plates, D, is 70 a cylindrical oven chamber, H, the ends of which are formed by the end walls, B, of the range. At each end of said chamber is a door, 11. In the space between the oven chamber, H, and the oven chambers, G, G, is 75 a deflector, 12, secured to the end walls, B, B, of the range and to the chamber, H, by 80 means of connecting pieces, 13. A pipe flue, 14, rises from the upper portion of the half-cylindrical top plate, E.

The course of the products of combustion 85 from the fire box or space in and immediately 90 above the grate is through the space between the sloping top walls of the chambers, G, and the deflector, 12, around the side edges of the latter and beneath the top plates, D, and then 95 around the cylindrical chamber, H, and into the flue pipe, 14. Such products of combustion impart heat to the top walls, 7, of the chambers, G, and to the deflector, 12, and heat radiated upward from the fire box meets 100 said deflector and is turned downward thereby to said walls, 7. The short upward walls, 6, of the chambers, G, are heated by conduction and radiation from the fire located between said walls. And by means of the 105 spaces, I, I, heat is transmitted to the bottom plates, 5, of the chambers, G, G, and the top walls, 2, of the chambers, F, F. From the fire upon the grate, there is lateral radiation

into said spaces, I, I, the heat rays striking the inclined top walls, 2, and imparting a portion of their heat thereto and being deflected upward so as to strike the bottom 5 plates, 5, 5. A greater quantity of heat is made to enter said spaces, I, by extending said grate below the level of the bottom walls, 5, 5; for, under such arrangement, a considerable portion of the body of fire is in position 10 to permit direct radiation into the spaces, I, I. Heat is also radiated downward from the fire on the grate to the upright walls, 1, 1, of the oven chambers, F, F. Thus heat is imparted to three walls of the chambers, G, G, 15 and to two walls of the chambers, F, F.

I claim as my invention:

1. In a cooking range, an oven chamber, a fire grate located beside the lower portion of said chamber, another oven chamber located 20 below said first mentioned chamber and separated therefrom by a space, and walls which, with the adjacent walls of said chambers, form a space passing beside said chambers and containing said grate and connecting 25 with the space between said chambers, substantially as described.

2. In a cooking range, an oven chamber, a fire grate located beside the lower portion of said chamber, another oven chamber located 30 below said first mentioned chamber and separated therefrom by a space fully open toward said grate, and walls which, with the adjacent walls of said chambers, form a space passing beside said chambers 35 and containing said grate and connecting with the space between said chambers, substantially as described.

3. In a cooking range, two horizontally opposite oven chambers, another two horizontally opposite oven chambers located above 40 said first mentioned chambers and separated therefrom by spaces and separated from each other by a space, a fire grate located in the lower portion of the space between said upper chambers, and walls forming a flue pas- 45 sage leading from the space above said grate across the upper walls of said upper chambers, substantially as described.

sage leading from the space above said grate, substantially as described.

4. In a cooking range, two horizontally opposite oven chambers, another two horizontally opposite oven chambers located above 50 said first mentioned chambers and separated therefrom by spaces and separated from each other by a space, a fire grate located in the lower portion of the space between said upper chambers, and walls forming a flue passage 55 leading from the space above said grate across the upper walls of said upper chambers, substantially as described.

5. In a cooking range, two horizontally opposite oven chambers separated from each 60 other by a space, another two horizontally opposite oven chambers located above said first mentioned chambers and separated therefrom by spaces and separated from each other by a space, a fire grate located in the 65 lower portion of the space between said upper chambers, and walls forming a flue passage leading from the space above said grate, substantially as described.

6. In a cooking range, two horizontally opposite oven chambers separated from each other by a space, another two horizontally opposite oven chambers located above said first mentioned chambers and separated therefrom by spaces and separated from each 75 other by a space, a fire grate located in the lower portion of the space between said upper chambers, and walls forming a flue passage 80 leading from the space above said grate across the upper walls of said upper chambers, substantially as described.

In testimony whereof I have signed my name, in presence of two witnesses, this 16th day of April, in the year one thousand nine hundred and eight.

HARRY M. SMITH.
